CLAIM

The ornamental design for a curved top pergola, as shown and described.

DESCRIPTION

FIG. 1 is a side-top perspective view of a curved top pergola showing our new design;

FIG. 2 is a bottom-side perspective view thereof;

FIG. 3 is a first side elevational view thereof;

FIG. 4 is a second side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken line portions of the drawing figures are included to show unclaimed subject matter only and form no part of the claimed design.

The dot-dash broken lines which define the bounds of the claim depict the limits of the claim and form no part of the claimed design.

1 Claim, 8 Drawing Sheets
